(57) **CLAIM**

We claim the ornamental design for a light, as shown and described.

DESCRIPTION

FIG. 1 is a perspective view of a light embodying the invention;

FIG. 2 is a front view of the light of FIG. 1;

FIG. 3 is a rear view of the light of FIG. 1;

FIG. 4 is a left side view of the light of FIG. 1;

FIG. 5 is a right side view of the light of FIG. 1;

FIG. 6 is a top view of the light of FIG. 1; and,

FIG. 7 is a bottom view of the light of FIG. 1.

In the drawings, the claimed design is defined by the shaded surfaces; the dash dot dash broken lines immediately adjacent shaded surfaces represent boundaries of the claim and form no part thereof; all other evenly spaced broken lines depict portions of the light that form no part of the claim.
